SIMULATED GEM

Louis Moyd, Clinton, Miss., assignor to Minerals Limited, Yonkers, N. Y., a corporation of New York

Application July 1, 1947, Serial No. 758,358

11 Claims. (Cl. 63—32)

1

The present invention relates to gems or jewels and more particularly to a simulated gem embodying an asterismal effect which may be readily manufactured.

A type of gem much sought after is that of the type generally referred to as a "star" sapphire, "star" ruby, "star" garnet, etc., which gems possess the property of exhibiting within the gem itself a star-shaped representation. Gem stones which exhibit this phenomenon are comparatively rare and hence they are highly prized. The starlike or asterismal effect exhibited by such gems seems to be due to reflection of light from regular arrangements or orientations of inclusions of minute size, or to lattice-like crystalline structure, present within the interior of the gem itself. Naturally occurring gems or stones of this type or variety are generally cut, or formed to rounded, convex, or cabochon form, as such provides an enhanced starlike effect when viewed under suitable lighting conditions.

Attempts have been made to artificially produce or imitate a starlike or asterismal effect, but the attempts have not proven commercially successful. Limitations of high cost, lack of perfection in the ultimate product, and manufacturing difficulties have barred commercial production of satisfactory star gems.

The present invention aims to overcome the above and other difficulties by providing a new, improved and commercially practicable article of manufacture capable of exhibiting a starlike or asterismal effect when viewed under suitable conditions of exposure or light.

An object of the present invention is to provide a new and improved article capable of exhibiting a starlike representation.

Another object of the invention is to provide a simulated gem which may be readily and inexpensively manufactured.

Still another object of the invention is to provide a gem adapted to exhibit an enhanced starlike effect.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

2

Fig. 1 is a plan view showing one form of the present invention;

Fig. 2 is an elevational view of the form illustrated in Fig. 1;

Fig. 3 is an enlarged fragmentary view showing a portion of the article illustrated in Figs. 1 and 2;

Fig. 4 is an enlarged fragmentary sectional view taken along the line 4—4 of Fig. 3;

Fig. 5 is a view showing additional forms of the present invention;

Fig. 6 is a view showing further forms of the invention; and

Fig. 7 is a view showing still other forms of the invention.

Referring more particularly to Figs. 1 and 2 of the drawings, there is shown an article of manufacture having an upper or normally exposed portion 1 of rounded, domed or convex shape 2. Stones cut to such rounded or convex form are generally referred to as "cabochons." Jewelers generally cut certain precious or semi-precious stones in this shape as the appearance of the gem is thereby enhanced. In plan view, the gem stone of Fig. 1 is shown of circular shape but it may be oval, rectangular, or any other desired shape. The under-surface of such a gem stone is generally substantially flat or has a much greater radius of curvature since this seems to provide an optimum reflecting surface; in some cases the underside or reflecting surface may even be slightly concave.

A six-rayed starlike or asterismal effect is indicated in Fig. 1, but with some materials, the star may, for example, have four rays.

As pointed out hereinabove, naturally occurring "star" sapphires, "star" rubies and the like exhibit asterism when viewed in reflected light and particularly when formed or cut so as to have a rounded or convex exposed surface; such naturally occurring gems are comparatively rare and hence are quite expensive.

By the present invention, the article or cabochon 1 may be of any suitable material which is substantially transparent or translucent.

Materials of this type may be naturally occurring gem stones which do not embody an asteriated structure, synthetic gem stones, simulated gem stones, glasses, plastics, etc. Such materials will generally be devoid of asterism.

In the present embodiment of the invention a starlike or asterismal effect is provided by a separate member 4 shown adjacent one side of the cabochon or gem stone 1. This separate member 4 is preferably mica of the phlogopite

variety but may comprise other naturally occur-

ring or synthetic materials capable of exhibiting asterism wherein an asterismal effect is produced by inclusions or the like preferably present throughout the body of the material. Such mica, that is, asteriated phlogopite, contains a plurality of minute needle-like inclusions of foreign matter, or cavities, or similar surfaces oriented in definite pattern dispersed throughout the material. Generally the principal axes of certain of the needle-like inclusions or cavities form angles of approximately 60 degrees and 120 degrees with other inclusions or cavities. Reflection of light from the surfaces of these oriented inclusions, cavities or the like in the mica gives a starlike or asterismal effect.

As will be clear from the foregoing description, the inclusions may be either minute cavities or minute particles of foreign material; the term "inclusions" as used herein is intended to cover the inclusion of foreign material as well as included cavities.

The beauty of the simulated gem may be even further enhanced by utilizing a covering element 1 having a greenish, bluish, ruby or other color. In some instances an actual sapphire, ruby or garnet, which is devoid of natural asterism, may be used with the present backing element 4 to thus very realistically simulate an asteriated gem-stone.

The mica layer or element or other suitable material 4 may be retained in position with the outwardly disposed element 1 by adhesive, by clamping the two together, as indicated by the dotted lines of Fig. 2, or by a combination of both adhesive and clamping. The types of cement or adhesives which may be used to secure the backing plate or element 4 of mica and the cabochon element 1 together are numerous, the primary requirement being that the particular adhesive be one which retains its property of transparency and preferably one which is unaffected by moisture, cleaning solutions, or the like. In some instances the particular type of adhesive may depend in part upon the composition of the cabochon and on the severity of treatment to which the final article may be subjected.

With some materials no adhesive is required to secure the backing element 4 and the cabochon element 1 together, a mechanical attachment being sufficient. In the case of glasses or plastics, the backing element 4 may be molded into the cabochon so as to form an integral part of it, as will be hereinafter described.

When the article of Figs. 1 and 2, comprising the outwardly disposed element 1 and the backing element 4 of mica, is viewed under suitable conditions of light or exposure, there may be seen a star-shaped figure having well-formed rays similar to those exhibited by natural "star" sapphires and "star" rubies.

While the embodiment of Figs. 1 and 2 shows an outwardly disposed element 1 having a rounded upper surface and a substantially flat, oppositely disposed surface, to which is secured the backing member 4, the rearward or reflecting surface of the element 1 may have a slightly convex or concave shape, as illustrated at 5, 7 and 8 in Figs. 5b, 5c and 5d. Also, the backing material itself (10, 11, 12, 13) may be of varying cross section or curvature, depending upon the particular enhanced effect desired.

Constructions of the hereinabove described type of simulated gem comprising the combination of an upper element 1 and a back element 4 may be generally referred to as "doublets."

In other instances, the simulated gem may have a third layer or element secured at the rear of the mica backing element to aid in giving the completed article a finished appearance and also to provide additional protection for the backing element. This form of the invention is illustrated in Fig. 6 of the drawings wherein the simulated gem may include an outer element (16, 17, 18, 19) having adhesively secured thereto a backing element of mica (22, 23, 24, 25) and a rearwardly disposed covering layer (28, 29, 30, 31). The rearwardly disposed layer may be of the same or similar material to that of the cabochon itself and, as indicated in Fig. 6, the backing element and the outer protective elements may be suitably shaped to provide a desired reflecting surface of the gem.

Instead of securing the elements together as above described, it may be desirable in some instances to mold a backing element, preferably of mica or other naturally occurring or synthetic materials such as those referred to hereinabove, into the material itself in such manner as to form an integral part of the article. Fig. 7 shows such an article. A backing element (35, 36, 37, 38) of this form of the invention is securely protected, cannot readily become separated from the complete article, and possesses the additional advantage of even more closely resembling a naturally occurring "star" sapphire, "star" ruby or other similar stone.

It will be seen that the present invention provides a new and improved simulated gem-stone having the property of exhibiting a starlike or asterismal effect when viewed under suitable lighting conditions. The gemstone may be readily produced and may be sold at but a fraction of the cost of naturally occurring "star" gem stones.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. An article of the class described comprising, a member of light-transmitting material having a generally domed surface, and a member of mica having a plurality of angularly disposed needle-like lines therein secured to said first member in spaced relationship with respect to a normally exposed surface thereof.

2. An article of the class described comprising, a member of light-transmitting material having a substantially convex surface at one portion thereof, and a mica member having a plurality of angularly disposed needle-like lines therein secured to said member in spaced relationship with respect to said convex surface.

3. A composite article of the class described comprising, a normally outwardly disposed light-transmitting member having a substantially domed surface at one portion thereof, and a layer of mica spaced from said domed surface having a plurality of oriented lineations, some of said lineations being angularly disposed with respect to other lineations.

4. An article of the class described comprising, a member of light-transmitting material having a generally curved surface, and a member of asteriated phlogopite secured to said first member in spaced relationship with respect to a normally exposed surface thereof.

5. A composite article of the class described

comprising, a normally outwardly disposed light-transmitting member having a substantially domed surface at one portion thereof, and a layer of phlogopite mica spaced from said domed surface having a plurality of oriented inclusions embodied therein, some of said inclusions being angularly disposed with respect to other inclusions.

6. An article of manufacture comprising the combination of a member of substantially transparent material having a convex surface, and a mica member having a plurality of angularly disposed needle-like inclusions therein and retained in assembled relationship with said first member substantially opposite said convex surface.

7. An article of manufacture comprising the combination of a member of substantially transparent material having an arcuate surface, and a member of mica having a plurality of angularly disposed needle-like cavities therein and retained in assembled relationship with said member substantially opposite said arcuate surface.

8. An article of manufacture comprising the combination of, a member of substantially transparent material having a convex surface, and a member of mica having a plurality of angularly disposed needle-like inclusions therein and adhesively secured to said member substantially opposite the convex surface thereof.

9. An article of manufacture comprising the combination of a member of substantially transparent material having a convex surface, and a member of mica having a plurality of angularly disposed needle-like inclusions therein and posi-

tioned intermediate outer surfaces of said member substantially opposite the convex surface thereof.

10. An article of the class described comprising, an outwardly disposed member of light-transmitting material having a surface with portions thereof at different elevations, and a backing member of naturally occurring substantially transparent mineral, having dispersed throughout the depth and area thereof a plurality of minute light-reflecting surfaces with some of said surfaces angularly disposed to others thereof, secured to said outwardly disposed member in spaced relationship with respect to a normally exposed surface thereof.

11. An article of the class described comprising, a front member of substantially light-transmitting material free of asterism having a surface with portions thereof at different elevations, and a layer of substantially transparent material embodying a plurality of angularly disposed needlelike inclusions of foreign matter dispersed throughout the depth and area thereof secured to said first member adjacent the rear thereof.
